(57) **CLAIM**

The ornamental design for a light emitting diode, as shown and described.

DESCRIPTION

FIG. 1 is a front side perspective view of a light emitting diode in accordance with a first embodiment of our new design;

FIG. 2 is a rear side perspective view of a light emitting diode in accordance with the first embodiment of our new design; FIG. 3 is a top plan view of the light emitting diode in accordance with the first embodiment of our new design;

FIG. 4 is a bottom plan view of the light emitting diode in accordance with the first embodiment of our new design; FIG. 5 is a front elevational view of the light emitting diode in accordance with the first embodiment of our new design;

FIG. 6 is a rear elevational view of the light emitting diode in accordance with the first embodiment of our new design; FIG. 7 is a right side end elevational view of the light emitting diode in accordance with the first embodiment of our new design;

FIG. 8 is a left side end elevational view of the light emitting diode in accordance with the first embodiment of our new design;

FIG. 9 is a front side perspective view of a light emitting diode in accordance with a second embodiment of our new design;

FIG. 10 is a rear side perspective view of a light emitting diode in accordance with the second embodiment of our new design;

FIG. 11 is a top plan view of the light emitting diode in accordance with the second embodiment of our new design;

FIG. 12 is a bottom plan view of the light emitting diode in accordance with the second embodiment of our new design;

FIG. 13 is a front elevational view of the light emitting diode in accordance with the second embodiment of our new design;

FIG. 14 is a rear elevational view of the light emitting diode in accordance with the second embodiment of our new design;

FIG. 15 is a right side end elevational view of the light emitting diode in accordance with the second embodiment of our new design; and,

FIG. 16 is a left side end elevational view of the light emitting diode in accordance with the second embodiment of our new design.

The broken line showing of environment (the remaining structure of the light emitting diode) in the FIGS. 1–16 is for illustrative purposes only and forms no part of the claimed design.
